SNAGGING GRINDER

George E. Comstock 3d, Holden, Mass., assignor
to Norton Company, Worcester, Mass., a corpo-
ration of Massachusetts

Application May 13, 1952, Serial No. 287,530

8 Claims. (Cl. 51—33)

1

The invention relates to snagging grinders. One object of the invention is to provide a snagging grinder which can be operated with little effort. Another object is to provide a thoroughly safe snagging grinder. Another object is to provide a snagging grinder of rugged yet simple construction and which is versatile so that it can snag small or large billets, short or elongated castings and can therefore be used for a variety of purposes in a steel plant or foundry.

Another object of the invention is to provide a snagging grinder capable of operating with higher pressures between the grinding wheel and the work piece than have hitherto been achieved in actual practice. Another object is to provide an economical grinder from the standpoint of grinding cost per unit volume of work. Another object of the invention is to provide a power operated snagging grinder so arranged that the operator's station is internally of the area occupied by the machine whereby the grinding wheel may be driven to send the detritus away from the machine and a dust collector system for one or many machines can be installed to collect the detritus without being in the way of the operator or operators. Another object is to provide a snagging grinder of such characteristics that it is movable along a track to produce the traverse between grinding wheel and work piece whereby several machines can be placed on the same track for simultaneous operation on a long piece of steel, or one machine can snag all of a long piece of steel.

Other objects will be in part obvious or in part pointed out hereinafter.

In the accompanying drawings illustrating one of many possible embodiments of the invention,

Figure 1 is a side elevation of the snagging grinder,

Figure 2 is an axial horizontal sectional view of the grinding wheel, wheel guard, wheel pulley and wheel mounting, the section being taken along the line 2—2 of Figure 1,

Figure 3 is a front elevation of the grinder,

Figure 4 is a vertical sectional view of one of the control valves,

Figure 5 is a diagram showing the fluid pressure connections,

Figures 6 and 7 are fragmentary views illustrating modifications of the invention.

Referring first to Figures 1 and 3, secured in any suitable manner to the floor 10 of the building where the grinder is located is a pair of parallel rails 11, 11 forming a track. The rails

2

11 can be embedded in a concrete floor and/or wooden ties can be used as in the case of a railroad track. A platform 12 constitutes the body of a car which runs on the rails 11; heavy bearing brackets 13 are secured to the under side of the platform 12 and receive axle shafts 14 on which are flanged wheels 15 which rest upon the rails 11.

One of the axles 14 has secured thereto a sprocket gear 16 which can be driven by a chain 17 extending from the gear 16 to a sprocket pinion 18 driven by a fluid motor 19. This fluid motor 19 is reversible and is secured to a plate 20 which is secured to one end of the platform 12.

Referring now to Figure 4, a valve lever 21 has a short portion 22 extending at right angles to the upstanding part of the valve lever and the outer end of the short portion 22 is connected by a link 23 to a flange 24 projecting from the cap 25 of a valve casing 26. A valve piston 27 with three "lands" is movable in a bore in the casing 26 which the lands snugly fit. The valve casing 26 has a pressure channel 28 and a pair of exhaust channels 29. I provide four duplicate valve casings 26 with the same moving parts and channels and these are aligned and bolted together with bolts 30. Each valve casing 26 has a pair of channels 31 and 32 for sending oil to and receiving oil from the piece of apparatus which the particular valve controls. Referring now to Figures 1 and 3, I provide a tank 33 which contains a supply of oil which is the "hydraulic" fluid to actuate the apparatus. On the cover of the tank 33 is a motor 34 whose motor shaft is coupled to a pump 36.

The output side of the pump 36 is connected to piping 37 which is connected to all of the pressure channels 28 by being connected to one thereof through an end cap 38 since these pressure channels 28 are cross connected to each other by a cross channel 40 which extends through each valve casing 26 and between them, suitable gaskets being provided to prevent leakage and the outer ends of the cross channel being blocked by the end cap 38 and another end cap 41 at the other end of the set of valve casings 26. Exhaust piping 42 extends to the end cap 41 and is connected to a cross channel 43 which cross channel 43 likewise extends through each valve casing 26 and between them connecting all of the exhaust channels 29 together, and the same gaskets and the caps 38 and 41 prevent leakage. The piping 42 runs to

the tank 33 to return the fluid thereto. In the piping 37 is a relief valve 44 the exhaust side of which is connected to the tank 33 and thus the system can be set to cause each of the pieces of apparatus to exert just so much force and no more. The intake side of the pump 36 is connected to the bottom of the tank 33 by means of piping 45.

The control apparatus has four valve levers, the valve lever 21 already identified and valve levers 52, 53 and 54; these are all alike and their connections to valve pistons corresponding to the valve piston 27 are all alike, in fact Figure 4 could be a section through any of the valve casings. Whenever any of the hand levers 21, 52, 53 or 54 is moved to the right, Figure 4, the channel 31 is connected to pressure and the channel 32 is connected to exhaust.

The fluid motor 19, adapted to be operated by oil under pressure, is connected by piping 56 to the channel 31 and by piping 57 to the channel 32. When oil flows to the fluid motor 19 through the piping 56 and returns from the motor 19 through the piping 57, which is when the operator sitting upon the stool 60 draws the lever 21 towards him, the motor 19 revolves in such direction as to move the car to the operator's left which is to the right in Figure 3, conversely when the operator pushes the valve lever 21 away from him, oil goes to the motor 19 through the pipe 57 and leaves it through the pipe 56 and this causes the car to move to the operator's right, which is to the left in Figure 3.

Referring to Figures 1 and 3, secured to the top of the platform 12 of the car is a base casting 63 having a massive central upstanding forked portion 64 and a pair of lateral upstanding forked portions 65. With its lower end located in the forked portion 64 and connected thereto by a heavy rock shaft 66 is a large upstanding rocker 67 having a forked top 68. Extending through the forked top 68 and connected thereto by a pin 69 is a horizontal overhead lever 70. A large depending lever 71 of generally open box shape is connected by a pin 72 to the front of the lever 70, the pin 72 extending through and between the sides of the lever 71 and through the lever 70. A grinding wheel 75 is located between a pair of disc-like enlargements 76 of the bottom of the sides of the lever 71 and is journaled therein on an axle shaft 77 to which the grinding wheel and also a double pulley 78 are secured.

Referring now to Figure 2, the disc-like enlargements 76 are connected by integral peripheral connecting portions 79 which form with the enlargements 76 a wheel guard for the grinding wheel 75 to keep the sparks and swarf from spraying upon the operator; the grinding wheel is intended to rotate clockwise as viewed in Figure 1 although because the stool 60 is not in line with the grinding wheel 75 that is to say is well removed from the plane of rotation of the grinding wheel 75, the grinding wheel could rotate counter-clockwise without great detriment but it is preferred not to have the swarf land upon the machine or any part thereof.

Referring now to Figure 1, one of the sides of the lever 71 has an upwardly and rearwardly extending portion 80 while the opposite side of the lever 71 has an upwardly and rearwardly extending offset portion 81 and located between these portions 80 and 81 is a bored enlargement 82 of a plate 83 and a pin 84 extends through the ends of the portions 80 and 81 and through

the bored enlargement 82 of the plate 83 thus pivotally mounting the plate 83 for movement up and down. Mounted on the plate 83 and secured thereto by bolts 85 is an electric motor 86 having on its armature shaft 87 a double pulley 88 connected by belts 89 to the double pulley 78. Of course the pulley 88 is keyed or otherwise fastened to the shaft 87, the pulley 78 is keyed or otherwise fastened to the axle shaft 77, and (see now Figure 2) a bushing 90 extending through the hole in the grinding wheel 75 is keyed to the axle shaft 77 while a nut 91 mounted on the threaded end of the bushing 90 and the opposite flanged end of the bushing 90 grip the sides of the grinding wheel 75 so that it can be driven by the rotation of the axle shaft 77, and as is customary suitable blotters, not shown, are interposed between the side of the wheel and the nut 91 and also between the side of the wheel and the flanged end of the bushing 90. Suitable bearings 92 and 93 are provided in the disc-like enlargements 76 to journal the axle shaft 77 and a nut and washer 94 secures the pulley 78 to the axle shaft 77 which is tapered at the end as shown. Thus whenever the motor 86 is energized, the grinding wheel 75 will be rotated, and I provide means to tighten the belts 89 at will as follows.

Extending through a boss 95 at the front end 30 of a forwardly extending portion 96 of the lever 71 is a stud 97 having a vertically bored enlargement 98 in threaded engagement with a screw 99 passing therethrough and the screw 99 has a reduced upper end 100 which extends through 35 a hole in the plate 83 and the reduced end 100 just fits the hole so that the resulting shoulder on the screw 99 can thrust the plate 83 upwardly while a washer and cotter pin 101 on the upper 40 end of the screw 99 serves to hold the parts from disengagement. By turning the screw 99 to raise it the belts 89 are tightened.

On the rear end of the lever 70 is a rearwardly extending forked enlargement 105 receiving the enlarged end 106 of a piston rod 107 whose piston, 45 not shown, is located in a cylinder 109 having a head 110 with an integral shaft 111 extending therefrom, the shaft 111 having on the lower end thereof an enlargement 112. The rocker 67 has a rearwardly extending forked portion 113 receiving the enlargement 112 through which and through the forked portion extends a pin 114 thus articulating the cylinder 109 to the forked portion 113. Similarly the piston rod 107 is articulated to the rearwardly extending forked enlargement 105 by means of a pin 115 extending through the enlargement 105 and the enlarged end 106.

Between the upwardly and rearwardly extending portion 80 and the bored enlargement 82 is 60 an enlarged end 118 of a piston rod 119 having a piston, not shown, in a cylinder 121 having a head 122 with an integral shaft 123 extending therefrom, the shaft 123 having an enlarged end 124 located in the rearwardly extending forked enlargement 105 and connected thereto by a pin 125 passing through the forked enlargement 105 and the enlarged end 124. Thus the cylinder 121 is articulated to the forked enlargement 105 while the piston rod 119 is articulated to the portion 80 of the lever 71.

The rocker 67 has on each side thereof a pair of laterally extending integral parallel flanges 130, each pair receiving the enlarged end 131 of a piston rod 132 having a piston, not shown, in a cylinder 134 having a head 135 with an integral shaft

136 extending therefrom with an enlarged end 137 located in one of the forked portions 65, and a pin 138 extends through the forked portion 65 and the enlarged end 137. Likewise a pin 139 extends through the flanges 130 and the enlarged end 131. It will be seen that there are a pair of cylinders 134, one on each side of the rocker 67, and the other parts are in duplicate so that the flanges 130 are articulated to the piston rods 132 and the cylinders 134 are articulated to the 10 forked portions 65.

Referring now to Figure 5, the several channels 31 and 32 are differentiated by the identification, below each pair, of one of the valve levers 21, 52, 53 and 54. The channel 31 of the valve controlled by the lever 52 is connected to piping 141 and the channel 32 of the same valve is connected to piping 142. The piping 141 is connected to hoses 143 and 144; the hose 143 is connected to the bottom of the left hand cylinder 134 (Figure 3) and the hose 144 is connected to the top of the right hand cylinder 134 (Figure 3). The piping 142 is connected to hoses 145 and 146; the hose 145 is connected to the top of the left hand cylinder 134 while the hose 146 is connected to the bottom of the right hand cylinder 134.

The channel 31 of the valve controlled by the lever 53 is connected to piping 151 and the channel 32 of the same valve is connected to piping 152. The piping 151 is connected to a hose 153 which is connected to the top of the cylinder 136 while the piping 152 is connected to a hose 154 which is connected to the bottom of the cylinder 109.

The channel 31 of the valve controlled by the lever 54 is connected to piping 161 and the channel 32 of the same valve is connected to piping 162. The piping 161 is connected to a hose 163 which is connected to the front end of the cylinder 121 while the piping 162 is connected to a hose 164 which is connected to the front end of the cylinder 121.

The motor 34 is energized by a cable 179 while the motor 86 is energized by a cable 171. The cable 171 and parts of the piping 151, 152, 161 and 162 are carried by a vertical support 72 extending upwardly from the car platform 12. This support 72 has a rearward extension 173 supporting a hose 175 which receives both cables 170 and 171 and extends to a swivel support 176 mounted on a stanchion 177 secured to the floor 10. Because the hose 175 is much longer than the distance between the extension 173 and the swivel support 176 when the former is right opposite the stanchion 177, the car can move quite a distance along the rails 11 without breaking the hose 175 or the cables 170 and 171 therein. The operator of course has available switches controlling the stopping and starting of the motor but it has not been deemed necessary to illustrate these.

It will now be seen that with the hand lever 21 the operator can move the car to a position to grind any part of the billet or steel plate or whatever it is that needs to be ground along the length thereof, that by means of the hand lever 52 the operator can tilt the rocker 67 which is an inverted pendulum to tilt the grinding wheel 75 in order to use the corner thereof to dig deep into the metal, that by means of the hand lever 53 the operator can raise and lower the grinding wheel and by means of the hand lever 54 he can move it towards and away from the car. The work piece, of course, will be supported on any suitable support extending parallel to the track

11, 11. It will be noted that the rock shaft 66 is at about a convenient level for the work piece whereby the grinding wheel can be tilted without any corresponding up or down movement.

5 When the operator draws the lever 21 towards him the rocker or pendulum 67 swings to the right, Figure 3, and when he pushes the lever 52 away from him the rocker or pendulum 67 swings to the left, Figure 3. When the operator draws the hand lever 53 towards him, the grinding wheel 75 rises and when he pushes the lever 53 away from him the grinding wheel 75 descends. When the grinding wheel contacts the work piece it presses against it with a force governed by the setting of the relief valve 44. This relief valve can have a hand wheel, lever or knob to set the pressure since adjustable relief valves are well known. However it will be noted that the weight of the motor 86, the weight of the depending lever 71 and most of the weight of the overhead lever 70 are added to the fluid pressure force. When the operator draws the hand lever 54 towards him the grinding wheel 75 moves forward and when he pushes the hand lever 54 away from him the grinding wheel 75 moves toward the rear of the machine. These statements are made on the basis of the connections as shown but it will readily be understood that the connections can be reversed wherever and whenever desired and that 20 includes the piping 56 and 57 to operate the motor 19.

The valve pistons 27 are normally maintained in neutral position by means of a device well known for such purpose consisting of a pair of washers 180 and 181 with an interposed spring 182, the assembly being held on a reduced end portion of the piston 27 by a nut 183 and the washer 180 therefore contacting a shoulder of the piston 27. The washer 183 cannot rise above the position shown in Figure 4 on account of a shoulder in the casing 26 while the washer 181 cannot descend below the position shown in Figure 4 by reason of a shoulder in a cap 185.

It will be seen that whenever a valve piston is 45 in the neutral or central position as shown in Figure 4, the fluid is locked in the cylinder or cylinders operated by the valve or, in the case of the motor 19, no fluid will flow through the motor. This feature is of importance especially in the 50 case of the cylinders 134 because when the operator releases the hand lever 52 the inverted pendulum 67 is held wherever he has put it. It is of importance also in the case of the cylinder 121 because the fluid locked in this cylinder holds 55 the depending lever 71 against the thrust of the grinding wheel. By means of the hand lever 53 controlling the cylinder 109 the operator can cause the grinding wheel 75 to press against the work piece with the combined forces due to the pull of gravity on the overhead masses and the fluid pressure, or he can hold the grinding wheel 75 at a fixed level by releasing the hand lever 53. Furthermore since there is a slight arcuate motion to the grinding wheel produced by operation 60 of the cylinder 121, the operator can use this arcuate motion as a fine downfeed.

It may be desired for some operations to allow the overhead weights to give the grinding pressure and to provide power means merely to lift the grinding wheel at will. In this aspect of the invention the pins 114 and 115 can be connected by power mechanism which will pull but not push as for instance by substituting a chain for the integral shaft 111. This modification is illustrated in Figure 6 in which the chain is numbered

190. A further modification is illustrated in Figure 7 in which the head 110 and the pin 114 are connected by a spring 191. This modification has the following advantage: if the grinding wheel 75 is on the work piece and the operator works the hand lever 53 so that the spring 191 is relaxed, the grinding pressure equals the pull of gravity on the entire mass carried by the overhead lever 70 with, of course, due allowance for masses to the right of the pin 69. Now if the operator moves the lever 53 to admit a little fluid through the hose 153 to shorten the connection, the spring 191 will be flexed somewhat thus creating a force which is subtracted from the total gravitational force thus diminishing somewhat the pressure between the grinding wheel and the work piece and the operator can continue to diminish this force until it reaches zero and eventually the grinding wheel 75 is raised. Thus, in the embodiment of Figure 7, the operator can adjust the grinding pressure and this is a considerable advantage for lots of snagging operations.

It will thus be seen that there has been provided by this invention snagging grinders in which the various objects hereinabove set forth together with many thoroughly practical advantages are successfully achieved. As many possible embodiments may be made of the above invention and as many changes might be made in the embodiment above set forth it is to be understood that all matter hereinbefore set forth or shown in the accompanying drawings is to be interpreted as illustrative and not in a limiting sense.

I claim:

1. A snagging grinder comprising a rock shaft, an inverted pendulum mounted on said rock shaft, an overhead lever articulated to said inverted pendulum at a point well above said rock shaft said overhead lever extending in a horizontal direction well away from said inverted pendulum, a depending lever articulated to said overhead lever at a point well removed from the point of articulation of said overhead lever in said horizontal direction, a grinding wheel shaft mounted in said depending lever at a point well below its articulation to said overhead lever, whereby a grinding wheel on said shaft can be tilted by moving said inverted pendulum, said grinding wheel can be raised or lowered by moving said overhead lever and said grinding wheel can be moved forwardly and rearwardly by moving said depending lever, power means to move said overhead lever to raise the grinding wheel, and power means to move and to hold said depending lever.

2. A snagging grinder according to claim 1 in which the power means to move the overhead lever is also adapted to move it to press the grinding wheel downwardly and to hold it at any position in which it is put.

3. A snagging grinder comprising a car, power means to move said car, an inverted pendulum mounted on said car, power means to move and

5 to hold said inverted pendulum, an overhead lever articulated to said inverted pendulum at a point well above said car said overhead lever extending in a horizontal direction well away from said inverted pendulum, a depending lever articulated to said overhead lever at a point well removed from the point of articulation of said overhead lever in said horizontal direction, a grinding wheel shaft mounted in said depending lever at a point well below its articulation to said overhead lever, power means to move and to hold said inverted pendulum, power means to move said overhead lever to raise the grinding wheel shaft, and power means to move and to hold said depending lever.

10 4. A snagging grinder as claimed in claim 3 in which said power means to move overhead lever is also adapted to move it to press downwardly the grinding wheel shaft and to hold said overhead lever at any position in which it is put.

20 5. A snagging grinder as claimed in claim 4 having a motor mounted on said depending lever at a position remote from said grinding wheel shaft, a pulley on said motor, a pulley on said 25 wheel shaft mounted in said depending lever at a pulleys.

30 6. A snagging grinder as claimed in claim 3 having a motor mounted on said depending lever at a position remote from said grinding wheel shaft, a pulley on said motor, a pulley on said grinding wheel shaft and a belt connecting said pulleys.

35 7. A snagging grinder as claimed in claim 1 having power means to move and to hold said inverted pendulum, and having spring means coupled to the power means to move said overhead lever to raise the grinding wheel whereby the weight of the depending lever can be counter-acted to a varying amount by the power means and the spring means to produce varying grinding pressures.

40 8. A snagging grinder as claimed in claim 7 having a motor mounted on said depending lever at a position remote from said grinding wheel shaft, a pulley on said motor, a pulley on said 45 grinding wheel shaft, and a belt connecting said pulleys, whereby the weight of the motor is added to that of the depending lever to produce grinding pressure and the grinding pressure can be counter-acted to a varying amount by the power means and the spring means to produce varying grinding pressures.

50 GEORGE E. COMSTOCK 3d.
